DRIVING CONNECTION MECHANISM

Maurice E. Hardy, Chicago, Ill., assignor to Zenith
Radio Corporation, a corporation of Illinois

Application February 5, 1952, Serial No. 270,056

3 Claims. (Cl. 74—200)

1

This invention relates to an improved driving connection mechanism particularly suited for use in a turntable driving system of the continuously variable speed type.

Multi-speed turntable driving systems are highly desirable in phonograph apparatus intended for use in the home, since records currently being sold may require rotation at 78, 45, or 33½ revolutions per minute for proper reproduction. More acceptable systems provide for continuous variation in driving speed over a range extending from about 10 to 85 revolutions per minute; they offer many advantages such as flexibility with respect to possible future record speeds and adjustability to satisfy the listener's personal preference as to the manner of reproduction. One type of continuously variable speed driving system is disclosed in the copending application of Ralph A. Mullaney, Serial No. 185,180 filed September 16, 1950, now Patent No. 2,615,342, issued October 28, 1952, and assigned to the same assignee as the present invention. The Mullaney arrangement utilizes a driving disc positioned parallel to the turntable and urged along its axis toward the turntable, and includes a mechanism for completing a driving connection between the turntable and the driving disc. This mechanism comprises an idler wheel interposed between the driving disc and the turntable and a movable carriage supporting the idler wheel. Ideally, the carriage should be free to move laterally along a line between the axes of rotation of the disc and the turntable and should permit substantially linear vertical movement of the idler wheel. While the described arrangement meets the desired operating characteristics and has been employed commercially with considerable success, it has been found that improvements may be made in its mechanical features.

It is an object of this invention, therefore, to provide a driving connection mechanism of the type described but having improved mechanical features.

It is a further object of this invention to provide a driving connection mechanism that is economical to manufacture and more simple and expedient to assemble.

In a driving system for a phonograph turntable including a driving disc positioned parallel to the turntable and urged along its axis toward the turntable, a mechanism for completing a variable-speed driving connection between the turntable and the disc is required. In accordance with the invention, this mechanism comprises an idler wheel interposed between the disc and the

2

turntable to effect a mechanical connection between them. An elongated stationary shaft is provided, and a movable carriage is positioned between the idler wheel and the shaft, the carriage supporting the idler wheel at one end thereof. At least one hook-shaped projection extends from the opposite end of the carriage in encompassing engagement with the shaft, and a resilient extension member also projects from the aforesaid opposite end of the carriage, engaging the shaft in diametrical opposition to the engagement of the hook-shaped projection. The engagement of the hook-shaped projection and the resilient extension member with the stationary shaft completes a mechanical linkage between the shaft and the carriage for guiding lateral movement of the carriage parallel to the shaft to adjust the speed of the turntable and for permitting pivotal movement of the carriage with respect to the shaft.

The features of the present invention which are believed to be novel are set forth with particularity in the appended claims. The present invention itself, both as to its organization and manner of operation, together with further objects and advantages thereof may best be understood by reference to the following description taken in connection with the accompanying drawing in which like parts are indicated by like numerals in the different figures, and in which:

Figure 1 is a plan view of a phonograph including a turntable driving system embodying the present invention, a portion of the turntable being broken away to reveal the driving system;

Figure 2 is a sectional view, partially schematic, taken along line 2—2 of Figure 1; and

Figure 3 is a perspective detail view of a portion of Figure 1.

The phonograph represented in Figure 1 includes a turntable 10 supported for rotation upon a mounting base 11. A central spindle 12 extends upwardly from the turntable and a record disc 13, shown in dash-dot outline, is centered thereby on the turntable. A tone arm 14 is pivotally affixed at one end of a conventional tone-arm shaft supported on base 11 and carries a stylus (not shown) engageable with the grooves of record disc 13. A driving disc 15 is positioned below and in parallel relation to turntable 10, and a mechanism to be described more fully hereinafter and including an idler wheel 16 interposed between the driving disc and turntable completes a variable speed driving connection therebetween. As more clearly shown in Figure

2, driving disc 15 is rotatably affixed to one end of a shaft 18 which is urged toward turntable 10 by a resilient member 19 engaging the free end of shaft 18. Preferably, the pressure of spring 19 is relieved whenever the phonograph is not in operation although the means for releasing the spring have not been shown in order to simplify the drawing. Spring member 19 is affixed to a sub-base 22, suspended from base 11, which also supports a driving motor 23 of the constant speed type. A driving connection between disc 15 and motor 23 is effected through a motor shaft 24 which is maintained in frictional contact with the periphery of disc 15.

The turntable driving system as thus far described is generally similar to that of the above-identified Mullaney application, and reference may be had thereto for mechanical details omitted from the instant drawing for purposes of simplification. More particular consideration will now be given to the mechanism, including idler wheel 16, which is constructed in accordance with the subject invention.

Idler wheel 16 of this mechanism is rotatably mounted on one end of a movable carriage 17, which is associated with mounting base 11 as clearly shown in the perspective view Figure 3. As indicated in that figure, carriage 17 terminates in a pair of hook-shaped projections 25 extending from the end of the carriage opposite that which supports idler wheel 16. These hook-shaped projections 25 are in encompassing engagement with an elongated stationary shaft 26 mounted in a U-shaped bracket 27 fixed to mounting base 11. A resilient extension member 28 also projects from this end of carriage 17 between hook members 25 and engages shaft 26 in diametrical opposition to the engagement of such hook-shaped members. An actuating arm 29 projects from the carriage parallel to the axis of shaft 26 and has a slot 32 for securing a pin 33 fixed to a speed-adjusting lever 34. Lever 34 is pivotally mounted on base 11 by a pivot pin 35 (Figure 1).

In operation, driving disc 15 rotates at a constant speed about shaft 18, driving impetus for the disc being supplied by motor 23 through the frictional contact between disc 15 and motor shaft 24. The disc 15 is urged into contact with idler wheel 16 by spring 19 which also urges idler wheel 16 into driving contact with turntable 10. Thus the rotary motion imparted to driving disc 15 by motor 23 is transmitted to turntable 10 through idler wheel 16. When change in the rotary speed of turntable 10 is desirable, the position of lever 34 may be changed, the movement thereof being imparted to movable carriage 17 through the linkage supplied by pin 33 and slot 32 of arm 29. Lateral movement of the carriage alters the position of idler wheel 16 with respect to the axes of rotation of driving disc 15 and turntable 10. If the idler wheel is displaced toward the axis of disc 15, the turntable speed is reduced, whereas displacement in the opposite direction increases the turntable speed.

In order that the system may operate efficiently, it is desirable for carriage 17 to effect lateral movement of the idler wheel 16 substantially in a path described by a plane including the axes of rotation of disc 15 and turntable 10. The shaft 26, which guides this lateral movement, is therefore mounted parallel to a plane including those axes of rotation. The hook-shaped members 25 maintain sufficiently close contact with the shaft to limit lateral movement to a direction parallel

to the shaft. The use of two hook-shaped projections 25 is strictly a matter of choice determined by considerations of convenience of assembly; it will be obvious to those skilled in the art that a single such member wide enough to limit the lateral movement of carriage 17 to a path parallel to shaft 26, will suffice. Resilient extension 28 maintains the shaft and carriage in positive engagement. The described linkage of carriage 17 and shaft 26 guides the movement of the carriage laterally parallel to the shaft while still permitting the carriage to pivot freely about the shaft. One of the chief advantages of the system is the elimination of speed irregularities and vibration due to possible irregularities in the frictional surfaces of disc 15 and turntable 10. Compensation for such surface variations is effected through the resilient bias supplied by resilient member 19 urging disc 15 into driving contact with turntable 10 through idler wheel 16. To make this "ironing-out" action effective, idler wheel 16 must be free to move along a substantially linear vertical path, since any restriction on such movement effectively reduces the advantage achieved through use of the resilient biasing structure. The length of carriage 17 is therefore made sufficiently great to limit vertical movement of idler wheel 16 to a substantially linear path.

The idler wheel 16, carriage 17, and the carriage mounting arrangement comprising shaft 26, hook-shaped projections 25, and resilient extension 28, provide an improved driving connection mechanism which permits unrestricted substantially linear vertical motion of idler wheel 16 while guiding lateral motion thereof along a line connecting the axes of rotation of driving disc 15 and turntable 10. The component parts utilized in construction of this mechanism are all relatively simple in form and comprise only such shapes as may be easily and economically manufactured. Assembly of the structure is both simple and expedient since the resilient nature of extension 28 allows complete assembly of the carriage structure before engagement with the stationary shaft 26.

While a particular embodiment of the present invention has been shown and described, it will be obvious to those skilled in the art that changes and modifications may be made without departing from the invention in its broader aspects, and, therefore, the aim in the appended claims is to cover all such changes and modifications as fall within the true spirit and scope of the invention.

I claim:

1. In a driving system for a phonograph turntable including a driving disc positioned parallel to said turntable and urged along its axis toward said turntable, a mechanism for completing a variable-speed driving connection between said turntable and said disc comprising: an idler wheel interposed between said disc and said turntable to effect a mechanical connection therebetween; an elongated stationary shaft; a movable carriage, positioned between said idler wheel and said shaft, one end thereof supporting said idler wheel; at least one hook-shaped projection extending from the opposite end of said carriage in partially encompassing engagement with said shaft; and a resilient extension member projecting from said opposite end of said carriage and in engagement with said shaft in diametrical opposition to the engagement of said hook-shaped projection to complete a me-

chanical linkage between said shaft and said carriage for guiding lateral movement of said carriage parallel to said shaft to adjust the speed of said turntable and for permitting pivotal movement of said carriage with respect to said shaft.

2. In a driving system for a phonograph turntable including a driving disc positioned parallel to said turntable and urged along its axis toward said turntable, a mechanism for completing a variable-speed driving connection between said turntable and said disc comprising: an idler wheel interposed between said disc and said turntable to effect a mechanical connection therebetween; an elongated stationary shaft; a movable carriage, positioned between said idler wheel and said shaft, one end thereof supporting said idler wheel; a pair of hook-shaped members extending from the opposite end of said carriage in partially encompassing engagement with said shaft; and a resilient extension member on said carriage projecting between said hook-shaped members and engaging said shaft in diametrical opposition to the engagement of said hook-shaped members to complete a mechanical linkage between said shaft and said carriage for guiding lateral movement of said carriage parallel to said shaft and for permitting pivotal movement of said carriage with respect to said shaft.

3. In a driving system for a phonograph turntable including a driving disc positioned parallel to said turntable and urged along its axis to-

ward said turntable, a mechanism for completing a variable-speed driving connection between said turntable and said disc comprising: an idler wheel interposed between said disc and said turntable to effect a mechanical connection therebetween; an elongated stationary shaft substantially parallel to said turntable and to a plane including the axes of rotation of said disc and said turntable; a movable carriage, positioned between said idler wheel and said shaft, one end thereof supporting said idler wheel; a pair of hook-shaped members extending from the opposite end of said carriage in partially encompassing engagement with said shaft; and a resilient extension member projecting from said opposite end of said carriage and in engagement with said shaft in diametrical opposition to the engagement of said hook-shaped members to complete a mechanical linkage between said shaft and said carriage for guiding lateral movement of said carriage parallel to said shaft and for permitting pivotal movement of said carriage with respect to said shaft.
